UNITED STATES PATENT OFFICE.

GILBERT RIMMER, OF WIGAN, ENGLAND, ASSIGNOR TO SULLIVAN MACHINERY COMPANY, A CORPORATION OF MASSACHUSETTS.

TRUCK.

Application filed December 13, 1919. Serial No. 344,732.

(GRANTED UNDER THE PROVISIONS OF THE ACT OF MARCH 3, 1921, 41 STAT. L., 1313.)

To all whom it may concern:

Be it known that I, GILBERT RIMMER, a subject of the King of England, residing at Wigan, in the county of Lancaster, England, have invented certain new and useful Improvements in Trucks (for which I have filed an application in England, Sept. 21, 1918, Patent No. 132,853), of which the following is a full, clear, and exact specification.

My invention relates to trucks.

It has for its object to provide an improved truck especially adapted to use in mines. A further object of my invention is to provide a mining machine truck of an improved and simplified construction whereby the machine may be transported from place to place on a mine track and close to the bottom in such a manner as to adapt it to use in narrow vein work in entries, and especially to service on narrow gauge tracks where there is little head room, a condition most often encountered in English mines. A still further object of my invention is to provide improved and simplified means for loading and unloading the machine and for moving the truck with the machine thereon from place to place, especially adapted to English mining conditions. These and other objects and advantages of my improved construction will, however, hereinafter more fully appear.

In the accompanying drawings I have shown for purposes of illustration one embodiment which my invention may assume in practice.

In these drawings,—

Fig. 1 is a side elevation of a truck equipped with my improvement and showing a mining machine about to be loaded thereon.

Fig. 2 is a side elevation of the truck with the mining machine in transport position thereon.

In this illustrative construction I have shown a truck frame 1 which may be of any usual type adapted slidably to receive a mining machine 2, herein illustrated as of the so-called "Longwall" type.

In my improvement it will be observed that the truck frame 1 is provided at each side of the same, and herein within the lines thereof and substantially beneath the center of gravity of the machine when the latter

is in transport position on the truck, with 55
slidable, track engaging supports 3, herein
a plurality of semi-circular and preferably
longitudinally spaced members, as shown,
rigidly connected by suitable connections,
such as bolts 4, to the under side of each 60
side member of the truck frame 1. As
shown, each of these members 3 is also
provided with flanges 5 adapted to engage
the inner edges of the rails 6 of the mine
track and thereby retain the truck frame 65
1 in the desired guided relation to the rails
as the truck frame slides longitudinally of
the latter.

It will also be noted that I have provided
upon the rear end of the truck frame 1 a 70
sheave, preferably centrally located and in
the form of an idler 7 as shown, and ro-
tatable on a horizontal axis 8. This sheave
is herein adapted to be engaged by the
flexible feed member 9 of a machine (here-
in in the form of a chain illustrated by
the usual chain line), and to cooperate
therewith during loading or transport. In
loading, the free end of the flexible feed
member 9 is extended, as shown in Fig. 1,
from the feed operating member 10 on the
machine, around the sheave 7, and attached
to an abutment in rear of the machine, here-
in in the form of a hook 11 located be-
neath the rear end of the frame 1. As a 85
result, when the feed member 10 is set in
motion to draw in the feed member 9, the
truck will be tilted, as shown, about its
front support 3 and the machine will be
fed along the feeding member and up the 90
inclined truck frame into transport pos-
ition thereon, the truck dropping back into
full engagement with the rails when that
position is reached. During transport, the
flexible feed member 9 is extended, as shown
in Fig. 2, around the sheave 7 and under
the truck frame 1 to a suitable abutment
in advance thereof, herein in the form of a
jack 12 which securely attaches the front
end of the member 9 to the bottom, the con-
struction being such that when the feed
operating member 10 of the machine is
operated to draw in its feed member, the
truck is slid along the rails toward the
jack in any of its successive positions along
the track, and under the guidance of the
flanged members 3. In unloading, it will
also be evident that by simply extending
100
105

the feed member from the feed operating member 10 forward along the side of the machine and above the truck frame to a forwardly located abutment, such as the 5 hooks 13, and then feeding the machine along the member 9 and relative to the truck, the machine may be readily unloaded when desired, the truck then tilting automatically about its front support 3 to facilitate this operation.

As a result of my improved construction, it will be observed that it is possible to provide a truck of an exceedingly simple and rugged construction which is adapted to use 15 in loading, transporting, or unloading a machine in narrow vein entry work, and especially to such work where the track is narrow gauge, the height of the truck, and therefore the over-all height of the machine 20 when mounted in transport position thereon, being reduced materially, i. e. a distance equal to more than half the height of the wheels on those wheel mounted trucks heretofore produced for such service, and this 25 without in any way interfering with the desired road clearance. It will also be observed that through my improved loading, transporting, and unloading means, it is possible to load, transport, or unload the 30 machine with facility. Attention is also directed to the fact that I have provided an exceedingly simple and rugged mechanism which is adapted to be manufactured at small expense. These and other advantages 35 of my improved construction will, however, be clearly apparent to those skilled in the art.

While I have in this application specifically described one embodiment which 40 my invention may assume in practice, it will be understood that this form of the same is shown for illustrative purposes and that the invention may be modified and embodied in other forms without departing from its 45 spirit or the scope of the appended claims.

What I claim as new and desire to secure by Letters Patent is:

1. In a truck, a truck frame adapted to receive a mining machine, and track engaging supporting transport skids beneath said frame.

2. In a truck, a truck frame adapted to receive a mining machine, and rail engaging supporting and guiding transport skids beneath said frame.

3. In a truck, a truck frame adapted to receive a mining machine, and flanged rail engaging transport skids supporting said frame.

4. In a truck, a truck frame adapted to receive a mining machine, and flanged rail engaging transport skids beneath the sides of said frame.

5. In a truck, a truck frame adapted to receive a mining machine, and flanged sub-

stantially semi-circular rail engaging supporting transport skids beneath the sides of said frame.

6. In a truck, a truck frame adapted to receive a mining machine and having laterally spaced side members, and a plurality of flanged longitudinally spaced rail engaging supporting transport skids beneath each side member of said frame.

7. In a truck, a truck frame movable over a trackway and adapted to receive a mining machine having a flexible feed member, a feed member engaging sheave rotatably mounted on a transverse axis at the rear end of said frame and so disposed that during transport said feed member may be directed around said sheave and beneath said truck frame to an extraneous point in advance thereof, and a feed member abutment to which the feed member is adapted to be attached during loading of the machine onto the truck frame.

8. The combination with a mining machine, of a truck frame adapted slidably to receive said machine, and a plurality of rail 90 engaging flanged skids longitudinally spaced and disposed beneath the sides of said truck frame and substantially beneath the center of gravity of said machine when the latter is in position on said frame.

9. In a truck, a truck frame adapted slidably to receive a mining machine, and a plurality of longitudinally spaced rail engaging transport skids disposed beneath each side of said frame and in rear of the front end thereof, the front skids being adapted to form a tilting axis for the frame during loading of a mining machine.

10. In a mining machine truck, a truck frame having longitudinally disposed guides 105 adapted to receive a mining machine having a flexible feed member, a feed member guide disposed on a transverse axis adjacent the rear end of said frame and adapted to direct said flexible feed member beneath said frame, and a feed member abutment disposed on said frame adjacent said guide.

11. In combination, a mining machine truck adapted slidably to receive a mining machine thereon and movable over a trackway, a mining machine on said truck having a flexible feeding member, and means for propelling said truck over the trackway and by the power of the mining machine thereon whereby said flexible feed member may be extended beneath said truck from the rear end thereof to a fixed point in advance thereof.

12. In combination, a mining machine truck adapted slidably to receive a mining machine thereon and movable over a trackway, a mining machine on said truck having a flexible feeding member, and means for propelling said truck over the trackway by the power of said mining machine including 130

a guide at the rear end of said truck whereby said flexible feeding member may be extended beneath said truck from the rear end thereof to a fixed point in advance 5 thereof.

13. In combination, a truck frame adapted slidably to receive a mining machine, supporting means for said frame, a feed member engaging sheave rotatably mounted 10 on a transverse axis at the rear end of said frame, a feed member engaging abutment disposed beneath the rear end of said frame, and a mining machine on said frame having a flexible feed member disposable rearwardly 15 and around said sheave to said abutment or from said sheave beneath said frame to a point in advance thereof, and means for fixing the free end of said feed member when disposed in the latter relation.

14. The combination with a mining machine having a flexible feed member, of a truck frame adapted slidably to receive said machine, flanged skids longitudinally spaced and disposed beneath each side thereof and substantially beneath the center of gravity 20 of said machine when on said frame, a feed member engaging sheave centrally located at the rear end of said frame and rotatable on a transverse axis, and means including a feed operating member on said machine and a plurality of abutments for moving said machine relative to said truck and feed member or said machine and truck relative to said feed member, one of said abutments 25 being located on said frame. 30 35

In testimony whereof I affix my signature.

GILBERT RIMMER.
